LIPSTICK HOLDER

Nathan Kasdan, New York, and Richard F. Landwehr, Woodside, L. I., N. Y., assignors to Majestic Metal Specialties, Inc., New York, N. Y., a corporation of New York

Application February 13, 1932, Serial No. 592,690

19 Claims. (Cl. 206—56)

This invention relates to lipstick holders of the type adapted to be operated entirely by one hand and has for its object to make a light weight, compact construction which is easy to open and close and in which the cover is positively actuated for both the opening and closing movement so that no spring opposes motion of the cover in either direction.

There have been several suggestions for lipstick holders which are adapted for one-hand operation in which the cover is removed and the material ejected all by a sliding knob actuated by the thumb while the device is held in the fingers of the same hand. One such suggestion has contemplated a thin flexible metal ribbon which is bent across an opening at one end and attached to a carrier at the opposite end, an actuating knob being secured to the ribbon intermediate its ends and projecting through a slot in the casing. The objection to this construction is that it has proven too heavy and bulky and the ribbon too fragile to withstand hard usage.

Another construction has contemplated a spring pressed cover but it has been found so difficult to open the cover against the action of the spring that two hands are generally necessary in order for the device to be operated.

In contrast to these constructions the present invention provides a more compact, light-weight, strong construction which uses no thin and easily deformed ribbon nor any spring actuated cover, the cover of the present invention being easily opened and closed with little effort by movement of the thumb alone. One factor contributing to the ease of opening the cover in the present construction is that the force to lift the cover is supplied at a substantial distance from the pivot with the result that the greater leverage requires less effort to raise the cover.

Referring to the drawings:

Fig. 1 is a longitudinal view of one embodiment of this invention with the cover closed.

Fig. 2 is a view corresponding to Fig. 1 but with the cover open.

Fig. 3 is a right side view of the device of Fig. 2.

Fig. 4 is a longitudinal section on the line 4—4 of Fig. 2.

Fig. 5 shows the outer portion of the outer tube or casing.

Fig. 6 shows the inner portion of the outer tube or casing.

Fig. 7 is a view of the slidable inner tube.

Fig. 8 shows the lipstick material which is slidable within the inner tube.

Fig. 9 is a longitudinal section through a portion of the device with the cover in closed position.

Fig. 10 is a perspective view of one of the cover elements.

Fig. 11 is a view corresponding to Fig. 1 but showing another modification of the invention.

Fig. 12 shows the device of Fig. 11 with the cover open.

Fig. 13 is a right side view of the device of Fig. 12.

Fig. 14 is an enlarged longitudinal section on the line 14—14 of Fig. 12.

Fig. 15 is a section on the line 15—15 of Fig. 13 but with the covers in closed position.

Fig. 16 is a detail of the outer tube or casing.

Fig. 17 is a detail of a friction plate.

Fig. 18 is a detail of the inner tube.

Fig. 19 is a perspective of one of the cover members.

In the embodiment illustrated in Figs. 1 to 10 inclusive, the outer casing 10 is shown as being provided with two cover portions 11, actuated by the knob 12 to open for ejection of the lipstick material 13, the knob 12 being slidable in the slot 14 of the outer casing 10.

The outer casing 10 is comprised of two portions, the outer portion shown in Fig. 5 and the inner portion shown in Fig. 6. The device is assembled by telescopically inserting the portion 15 within the outer part 10 when the stamped-out projection 16 on the inner portion 15 engages the inside of a correspondingly stamped-out portion 17 on the outer part, whereby the two parts of the outer tube or casing are resiliently or yieldably connected to function as a single part. At the top of the inner portion 15 are provided the knuckles 18 carrying the cover pintles. The sides between the knuckles are recessed or cut out as shown at 19 so that the downwardly extending side flange portions of each cover may engage within this recessed part when the cover is closed as shown in Fig. 9. The slot 20 in the inner portion 15 is wider than the slot 14 in the outer portion 10 for a purpose to be hereinafter described.

Slidably received within the portions of the outer tube or casing, that is within the tube 15, is the carrier guide tube or cover actuator 21. This tube also has an inclined longitudinal slot 22, the lower end of which is provided with a transversely extending portion 23, as shown in Fig. 7. Outwardly extending pins 24 are provided to ac-

tuate the covers 11. Slidable within the inner tube 21 is the carrier 25 having the transverse slot 26, said carrier holding the lipstick material or pencil 13.

5 As shown in Fig. 4 the actuating knob 12 is provided with a shank, pin or stem 27 having a reduced portion 28 adjacent the knob and where the stem passes through the outer portion 10 of the outer casing. The slot 14 in the outer portion 10 is narrower than the slots 20, 22 or 26, with the result that when the reduced portion 28 of the knob stem is engaged within the narrow slot 14 the knob is prevented from being withdrawn or falling out of the device. The upper end of the 15 narrow slot 14 is enlarged to permit insertion of the stem 27 during assembly.

The cover portions 11 are mounted on pintles 29 passing through the knuckles 18 and each cover portion 11 has side flanges 30, shown in Figs. 9 20 and 10. One of these side flanges 30 of each cover portion is provided with a curved slot 31 of the general shape indicated. In each slot 31 is placed one of the pins 24.

To assemble the device illustrated, the inner 25 portion 15 of the outer tube or casing is placed within the outer portion 10 and yieldably locked therein when the projection 16 engages the recessed portion 17. The inner tube 21 is then placed within the outer tube. The carrier 25 and material 13 may then be inserted in the inner tube. Before pushing the carrier 25 well down inside the inner tube 21 it is desirable to insert the actuating knob 12 into the upper end of the slot 14 so that the stem 27 of the knob 12 passes through 35 the slot 20, the slot 22 and engages the slot 26 in the carrier 25. The cover portions 11 are next mounted on their respective pintles 29 with the pins 24 engaging the slots 31, as shown in Fig. 3. When the device has been thus assembled the 40 actuating knob may be pushed down, withdrawing the carrier and material 13 within the inner tube 21. During the first portion of the downward movement of the actuating knob 12 there will be no relative movement between the inner 45 and outer tubes because their slots are all in alignment but after the stem 27 of the knob 12 reaches the end of the slot 22 in the inner tube, it then causes the inner tube 21 to slide with the carrier 25 during the balance of the downward movement 50 of the knob. This downward movement of the inner shutter tube 21 closes the slot 14 and also causes the pins 24 sliding in the slots 31 to close the covers 11. As shown in Fig. 9 the pins 24 are only the thickness of the flanged portions 30 of 55 the covers.

During the latter part of the downward movement of the actuating knob 12 the shank 27 is guided by the coaxial slots 14 and 20 of the outer tube and these slots cause the shank 27 to be moved transversely within the lower end portion of the slot 22, as well as transversely within the slot 26 of the carrier 25. The dotted lines in Fig. 1 show the position of the slot 22 of the inner tube 21 when the carrier is completely lowered and the covers closed. In this position it will be seen that the inner tube 21 closes the slots 14 and 20 of the outer tube or casing.

On moving the actuating knob 12 upwardly from the position shown in Fig. 1 the shank 27 70 first causes the carrier 25 and inner tube 21 to be simultaneously raised until the shank 27 is within the inclined slot 22 of the inner tube and this slot 22 is aligned with the slots 14 and 20 of the outer tube. As soon as these slots are aligned, 75 outward movement of the inner tube ceases and

continued raising of the knob 12 functions only to raise the carrier 25 and material 13. Since the pintles 29 are carried within the knuckles 18 of the outer casing, it will be appreciated that outward movement of the inner tube 21, raising the pins 24, simultaneously raises the cover portions 11. The device is preferably proportioned as indicated so that the covers raise a sufficient amount to allow the material 13 to be ejected without the material contacting with the cover, since this material is of a soft cake type that would otherwise be worn away by the covers.

Among the advantages of this invention may be enumerated the fact that the device is readily operable by the thumb while the outer casing is 15 held in the fingers of the same hand, thus requiring the operator to use only one hand. Inasmuch as a lady frequently carries packages or a pocketbook or gloves or other articles in one hand, the value of this device will be better appreciated. 20

Another advantage is the ease of opening the covers since there are no springs which oppose movement of the covers in either direction.

Another advantage is the compact design and arrangement in order that the device may occupy 25 small dimensions.

While plated brass or other readily stamped metal may be used in forming this invention, nevertheless aluminum or aluminum alloys may be used to provide additional lightness in weight. 30

The use of two covers instead of one necessitates less movement of the inner tube before both covers are opened a sufficient amount for ejection of the material 13. The pins 24 which transmit the opening thrust to the covers are spaced from 35 the pintles and this leverage is another reason why the covers are easy to actuate. It will be seen that a notable feature is the positive actuation of the covers in both the opening and closing movements. 40

Another feature is the arrangement of the slots 14 and 20 so that the constricted width to the slot 14 prevents the shank 27 of the knob 12 coming out and causes it to be locked in position during normal operation. 45

The device shown by Figs. 11 to 19 inclusive is another embodiment of this invention which is similar in purpose and function to that shown by Figs. 1 to 10 inclusive. The drawn metal casing or outer tube 32 is closed at its lower end and provided with a slot 33 along which moves the actuating knob for the covers, lipstick carrier and inner tube. The casing 32 is provided with integral bent metal knuckles 34 on opposite top edges as shown in Fig. 16 for the purpose of having the cover portions 35 pivotally secured thereto. The actuating knob 36 passes through the cover actuating and carrier guide tube 37 and into the lipstick carrier 25 as in the previous construction of Figs. 1 to 10. The tube 37 also functions as a shutter for the slot 33. 55

The inner tube 37 is made of bent metal strip having a longitudinal slit 38 of the shape illustrated where the ends of the metal strip contact. Here again the inner tube is provided with an inclined longitudinal slot 39 of the same shape as that in the inner tube of Fig. 7 and is provided with a transverse lower end portion 40 for the same purpose. In order to space the inner tube from the walls of the casing the inner tube 70 is shown as being provided on three sides with stamped out fingers lugs or tongue portions 41 which frictionally engage the casing walls. Instead of having such tongues on the front side of the inner tube containing the slot 39 a sepa- 75

rate friction or shutter plate is used as shown in Fig. 17. This plate 42 is also provided with an inclined slot 44 and a series of stamped out tongue portions 43. The plate 42 moves with the inner tube 37 in closing the slot 33 in the casing 32 in the position shown in Fig. 11 when the cover portions 35 are closed and the lipstick 13 withdrawn into the inner tube and casing.

A pair of slots 45 are provided one side of the inner tube adjacent its upper edge as shown in Fig. 18. These slots receive the cover pin 46 there being one pin in each slot. This pin and slot connection is the same as that shown in the preceding embodiment of Figs. 1 to 10 except that the slots are here located in the inner tube while the pins are carried by the cover flanges 49, just the reverse of what is shown in Fig. 3. Instead of being curved the slots 45 in Fig. 18 are shown of nonuniform width. Preferably these slots and the pins are located far enough away from the cover pivot to provide sufficient leverage for easy operation of the covers when the actuating knob 36 is moved by the thumb while the device is held in one hand.

The shank of the actuating knob 36 is shown as being provided with a reduced portion 47 around which fits a washer 48 of any convenient form. This washer 48 is placed in position after the lipstick holder has been assembled but without the lipstick material being in place.

To assemble the device of Figs. 11 to 19 the inner tube 37 and the friction plate 42 are together inserted within the casing 32. The cover portions 35 are then secured by pivot pins to the casing knuckles 34 with the pins 46 engaging the slots 45. The carrier 25 is of the same shape as that shown in Figs. 4 and 8 and is next inserted within the inner tube. The actuating knob 36 is then inserted through casing 32 plate 42, inner tube 37 and the transverse slot of the carrier. The actuating knob is then moved to a position at the upper end of its travel when said knob and its shank can have the washer 48 attached.

Stamped out tongue portions may also be provided, if desired, adjacent the top of the inner tube in order to space the top of the tube as well as the bottom from the casing walls, but such tongues must be shaped so as not to catch on the knuckles of the cover hinges. When the pin and slot connection between the inner tube and covers are shaped as illustrated, these connections may also serve to position and guide the upper end portion of the inner tube and prevent its catching on the cover hinge knuckles. The slot in the friction plate is of the same size and shape as the slot in the inner tube. The inner and outer tube etc., may be made of brass provided with chromium plating or other suitable finish, or if desired they may be made of German silver or other alloys capable of presenting an attractive finish.

We claim:

1. A dispensing holder comprising a casing, a carrier for material to be discharged and slideable within said casing, a pivotal closure for said casing where the material is ejected, an inner tube, an actuating knob projecting through a longitudinal slot in said casing, and means connecting said closure with said knob whereby the closure may be positively opened and closed by movement of said knob and said carrier simultaneously moved to eject material from said casing, said knob having a reduced portion where passes through the casing and said casing having at least a portion of its slot of smaller

width than the slot in said inner tube whereby said knob is retained in place.

2. A dispensing holder comprising a casing, a carrier for material to be discharged and slideable within said casing, a pivotal closure for said casing where the material is ejected, an inner tube, an actuating knob projecting through a longitudinal slot in said casing, and means connecting said closure with said knob whereby the closure may be positively opened and closed by movement of said knob and said carrier simultaneously moved to eject material from said casing, said knob having a reduced portion where it passes through the casing and said casing having at least a portion of its slot of smaller width than the slot in said inner tube whereby said knob is retained in place, said slot in the outer casing having an enlarged end through which said knob may be removable.

3. A lipstick holder comprising an outer tube, an inner tube, a carrier for lipstick material slideable within said inner tube, a cover, an actuating knob extending through the outer tube and connections between the inner tube and carrier and between inner tube and cover for simultaneously raising said cover and sliding the inner tube partway out of the outer tube and on continued movement of said knob moving the carrier to eject the lipstick material, said connections including a pin on said knob engaging said tubes through parallel inclined slots, the slot in the inner tube being provided with a transversely disposed end portion to effect a movement of said inner tube during only partial movement of the carrier.

4. A dispensing holder comprising a casing, a carrier for material to be discharged and slideable within said casing, a pivotal closure for said casing where the material is ejected, an actuating knob projecting from said casing, means connecting said closure with said knob whereby the closure may be positively opened and closed by movement of said knob and said carrier simultaneously moved to eject material from said casing, said means including an inner casing slideable in the first mentioned or outer casing by means of said knob, both of said casings being provided with slots which do not coincide throughout their lengths whereby the inner casing may be movable by said knob to close the slot in the outer casing when said closure is shut, said slots being parallel and inclined, the inner slot being provided with a transverse offset portion at its end remote from the closure.

5. A lipstick holder comprising an outer tube, an inner tube, a carrier for lipstick material slideable within said inner tube, a pivotal cover, an actuating knob extending through the outer casing and connections between the inner tube and carrier constructed for simultaneously raising said cover and sliding the inner tube partway out of the outer tube and on continued movement of said knob moving the carrier to eject the lipstick material, said cover being connected to said inner tube by a pin and slot connection on a side non-parallel with the cover pivot, said tubes having inclined parallel slots and one of said slots having a transverse offset portion in and out of which said actuating knob may be moved by the other parallel slot.

6. A holder comprising an outer casing having a longitudinal slot therein, a carrier within the casing, an actuator for the carrier extending out of the casing through said slot, a shutter within the casing for closing the slot when the carrier

is retracted and opening the slot as the carrier is moved outwardly, said shutter having a longitudinal slot therein adapted for registration with at least the major portion of the casing slot, said 5 shutter slot also having an offset portion fixed out of alignment with respect to the major portion of the shutter slot and said casing slot, whereby movement of said actuator in the lower portion of said casing slot and at the same time in said 10 offset portion of the shutter slot causes the shutter to close said casing slot.

7. A holder comprising an outer casing, of polygonal cross section having a longitudinal slot therein on one face, a carrier within the casing, an actuator for the carrier extending out of the casing through said slot, a cover movable in response to travel of the actuator in said slot, said slot being inclined from adjacent one corner of one side of the casing to adjacent a diagonally 20 opposite corner of the same side of the casing.

8. A container of the class described comprising a casing having a longitudinal slot, a closure for said casing, a closure operator longitudinally movable in said casing, a carrier longitudinally 25 slideable in said casing, said carrier constructed to move independently of said closure operator, means for effecting releasable engagement between said closure operator and said carrier during the initial movement of the latter to impart 30 motion to the closure operator, means for arresting the movement of said closure operator while permitting continued movement of the carrier, said first named means including a longitudinal slot in said closure operator having a lateral extension 35 at its lower end to provide a shoulder, and means engaging said carrier and extending through said slots for manual operation of said carrier.

9. A cosmetic holder comprising an exterior 40 casing, an interior sleeve slideable longitudinally of the exterior casing, a closure for the exterior casing movable to open and closed position in response to movement of said interior sleeve, a spring strip between the exterior casing and the 45 interior sleeve, and a cosmetic carrier recipro- cable in said interior sleeve to alternately project cosmetic for use and withdraw it for carriage.

10. A holder comprising a casing having a longitudinal slot therein, a cover for the casing, a 50 carrier within the casing, an actuator for the carrier extending out of the casing through said longitudinal slot, a shutter within said casing and between said carrier and casing for closing the longitudinal casing slot as the carrier is retracted 55 and for opening the casing slot as the actuator and carrier are moved outwardly, said longitudinal casing slot being inclined and said shutter being of a size and so proportioned relative to the casing that the casing forms a guide for the 60 same, said shutter also having a lateral recess in an end portion whereby said actuator may move the shutter to uncover the casing slot.

11. A holder comprising a casing having a longitudinal slot therein, a cover for the casing, a 65 carrier within the casing, an actuator for the carrier extending out of the casing through said longitudinal slot, a shutter within said casing and between said carrier and casing for closing the longitudinal casing slot as the carrier is retracted 70 and for opening the casing slot as the actuator and carrier are moved outwardly, said shutter being provided with a lateral recess at one end portion thereof into which said actuator may be guided for moving said shutter, said lateral recess 75 being of greater width than the casing slot and

the portion of the actuator contiguous the shutter being larger than the portion passing through the casing slot, a portion of said casing slot being enlarged to allow insertion of said actuator through the casing.

12. A holder comprising a casing having a longitudinal slot therein, a cover for the casing, a carrier within the casing, an actuator for the carrier extending out of the casing through said longitudinal slot, a shutter within said casing and between said carrier and casing for closing the longitudinal casing slot as the carrier is retracted and for opening the casing slot as the actuator and carrier are moved outwardly, said shutter being provided with a lateral recess at one end portion thereof into which said actuator may be guided for moving said shutter, a pivotal connection between said shutter and cover, and guide means for each end portion of said shutter so arranged that movement of each end of the shutter is substantially parallel with the movement of the opposite end thereof.

13. A holder comprising a casing having a longitudinal slot therein, a cover for the casing, a carrier within the casing, an actuator for the carrier extending out of the casing through said longitudinal slot, a shutter within said casing and between said carrier and casing for closing the longitudinal casing slot as the carrier is retracted and for opening the casing slot as the actuator and carrier are moved outwardly, said shutter being provided with a lateral recess at one end portion thereof into which said actuator may be guided for moving said shutter, a pivotal connection between said shutter and cover, said connection being entirely within the casing when the cover is closed, and a pivotal connection between the cover and casing located at substantially the top of the casing and said shutter extending slightly out of the casing when the cover is fully 40 opened, said cover when open being substantially close to the plane of the sides of the casing.

14. A holder comprising a casing having a longitudinal slot therein, a cover for the casing, a carrier within the casing, an actuator for the carrier extending out of the casing through said longitudinal slot, a shutter within said casing and between said carrier and casing for closing the longitudinal casing slot as the carrier is retracted and for opening the casing slot as the actuator and carrier are moved outwardly, said shutter being provided with a lateral recess at one end portion thereof into which said actuator may be guided for moving said shutter, a pivotal connection between said shutter and cover, and guide means for the end portion of the shutter adjacent said cover, which is independent of the cover, and which causes that end of the shutter to move parallel to itself, the cover and shutter having a pin and slot connection therebetween.

15. A holder comprising a casing having a longitudinal slot therein, a pair of covers for the casing, each closing substantially half the casing, a carrier within the casing, an actuator for the carrier extending out of the casing through said longitudinal slot, a shutter within said casing and between said carrier and casing for closing the longitudinal casing slot as the carrier is retracted and for opening the casing slot as the actuator and carrier are moved outwardly, said shutter being provided with a lateral recess at one end portion thereof into which said actuator may be guided for moving said shutter, a pivotal connection between said shutter and covers, said connection being entirely within the casing when the

covers are closed, and a pivotal connection between the covers and casing located at substantially the top of the casing and said shutter extending slightly out of the casing when the covers are fully opened, the covers each having a movement of substantially less than 180° and each having a flange insertable between said casing and carrier.

16. A holder comprising a casing having a longitudinal slot therein, a pair of covers for the casing, each closing substantially half the casing, a carrier within the casing, an actuator for the carrier extending out of the casing through said longitudinal slot, a shutter within said casing and between said carrier and casing for closing the longitudinal casing slot as the carrier is retracted and for opening the casing slot as the actuator and carrier are moved outwardly, said casing slot being substantially symmetrically disposed with respect to the casing axis, the shutter having a lateral recess adjacent one end and with which the actuator is engaged in moving the shutter with respect to said casing slot, a pivotal connection between the shutter and the covers, each cover being provided with side flanges adapted when the covers are closed to be close to the casing.

17. A holder comprising a casing having a longitudinal slot therein, a cover for the casing, a carrier within the casing, an actuator for the carrier extending out of the casing through said longitudinal slot, a shutter within said casing and between said carrier and casing for closing the longitudinal casing slot as the carrier is retracted and for opening the casing slot as the actuator and

carrier are moved outwardly, the shutter having a lateral recess adjacent one end and with which the actuator is engaged in moving the shutter with respect to said casing slot, and frictional spring fingers on the shutter.

18. A holder comprising a casing having a longitudinal slot therein, a cover for the casing, a carrier within the casing, an actuator for the carrier extending out of the casing through said longitudinal slot, a shutter within said casing and between said carrier and casing for closing the longitudinal casing slot as the carrier is retracted and for opening the casing slot as the actuator and carrier are moved outwardly, the shutter having a lateral recess adjacent one end and with which the actuator is engaged in moving the shutter relatively to said casing slot, a guide tube for the carrier, and means for yieldably spacing at least one end portion of said tube from said casing.

19. A holder comprising a casing having a longitudinal slot therein, a cover for the casing, a carrier within the casing, an actuator for the carrier extending out of the casing through said longitudinal slot, a shutter within said casing and between said carrier and casing for closing the longitudinal casing slot as the carrier is retracted and for opening the casing slot as the actuator and carrier are moved outwardly, the shutter having a lateral recess adjacent one end and with which the actuator is engaged in moving the shutter relatively to said casing slot, a guide tube for the carrier, located inwardly of the shutter.

NATHAN KASDAN.

RICHARD F. LANDWEHR. 35
